Patented Feb. 8, 1916.

UNITED STATES PATENT OFFICE.

ULRICH SPRINCHORN AND OSCAR KALLANDER, OF JAMESTOWN, NEW YORK.

WINDOW-SHADE FIXTURE.

1,171,362.

Specification of Letters Patent.

Patented Feb. 8, 1916.

Application filed July 8, 1915. Serial No. 38,723.

To all whom it may concern:

Be it known that we, ULRICH SPRINCHORN and OSCAR KALLANDER, subjects of the King of Sweden, residing at Jamestown, in the 5 county of Chautauqua and State of New York, have invented certain new and useful Improvements in Window-Shade Fixtures, of which the following is a specification.

The present invention relates to improvements in windowshade fixtures designed primarily with the object of providing a guide for controlling the rolling action of a windowshade and a stop for limiting its movement.

15 A further object in view is to provide a device of this character which will permit of a wide range of adjustability and embodying means for holding its adjustable sections in adjusted positions.

20 With the above and other objects in view, this invention consists of certain combinations, constructions and arrangement of parts all as hereinafter more fully described, claimed and illustrated in the accompanying drawing, wherein:

Figure 1 is a perspective view showing the application of the preferred embodiment of the invention. Fig. 2 is a fragmentary elevation thereof. Fig. 3 is a transverse sectional view taken about on the plane indicated by the line 3-3 of Fig. 2. Figs. 4 and 5 are transverse sectional views taken on the lines 4-4 and 5-5 respectively of Fig. 2. Fig. 6 is a top plan of an end portion of this device. Fig. 7 is a fragmentary perspective view showing a slightly modified form of the invention.

Throughout the following detail description and on the several figures of the drawing, similar parts are referred to by like reference characters.

Referring to the drawing, the numeral 1 designates a window frame of conventional form and construction to the top portion of which, and at each side are attached supporting clips 2 upon which is supported the device forming the subject-matter of this invention. The same comprises a body member or rod consisting preferably of adjustable sections 3, 4, each of which is substantially the same in configuration and form. It will be noted by reference to Fig. 2 particularly that the adjustable sections 3, 4 overlap one another and the inner end of each is bifurcated as shown most clearly in

Fig. 5 at 5, the bifurcate portion being bent laterally and clamped around the contiguous adjustable section so as to constitute a sliding connection between said sections.

The end portion of each section is first 60 bent downwardly or approximately at right angles to its major portion as indicated at 6, then inwardly at right angles again to form a recurved guide element 7, the material being again recurved as indicated at 8 to form 65 a coöperating guide element in the same horizontal plane as the guide element 7, but slightly spaced therefrom, the extremity of the section being finally bent upwardly to form a shade supporting or engaging arm 9. 70 This latter portion, it will be observed by reference to Fig. 3, slightly offstands from the guide loop formed by the elements 7, 8, so that when the window shade 10 is in position upon the arm 9, the material of said 75 shade may extend downwardly through the guide loop as shown in this figure. As hereinbefore premised, the coöperating section of the device is similarly formed so that when said sections are in operative position 80 upon the window frame they will support the windowshade in the usual manner. This shade, as is customary, is provided with the stick or rod stiffening member 11 at its lower or free end, and in the use of the 85 article forming the subject-matter hereinbefore described, the rolling action of the curtain is controlled by the guide loops coöperating with each side of the curtain so that the curtain or shade will roll evenly upon its 90 supporting roller. In addition the guide loops are adapted to coact with the stiffening member 11 when the shade is raised to limit the rolling movement and prevent like-lihood of the shade being caught between 95 the frame and its body portion or slipping around and unwinding the spring, a very usual occurrence with windowshades.

It will be obvious that the rod sections 3 and 4 may be suitably adjusted to accord 100 with different widths of window frame as well as window shades that may be supported thereby and accordingly the clips 2 with which the rod sections frictionally engage are designed to be attached at proper spaced position upon the frame as by means of screws 2'. In order to hold the rod sections at adjusted positions, locking means are provided, consisting of clips slidably mounted upon the overlapping portions of 110

said sections, any desired number of said clips being employed to properly carry out the function of this device. The important feature of these clips is that upon sliding 5 one of the same laterally toward the end of one section adjacent to the point where it is bent about its coöperating section, said clip forms a wedge by reason of the fact, primarily, that the space between the sections 10 at this point is reduced and the further reason that the yieldability of the material is likewise less at this portion. Advantage is taken of this to obtain frictional clamping action or connection of the sections which 15 will prevent the sections from being extended or contracted when one or more of the clip members is in position adjacent to the connecting ends of the respective sections.

It will be noted from the drawing that the 20 clips, denoted 12 are formed by bending a piece of metal in one direction about one of the sections and in the other direction about the other section, therefore being substantially in the shape of the figure 8, in 25 cross section, the material of said clip obviously passing between the respective sections. It is this intermediate part of the clip which forms the wedge and by comparison of Figs. 4 and 5 the difference in the 30 space between the rod sections will be more apparent. As shown in the preferred construction of the device, three of these clips are employed one at each side and one intermediate and the intermediate clip is de- 35 signed to perform its own special function of preventing the separation of the sections when the lateral clips are shoved into wedging position. It is this intermediate clip, therefore, that makes the lateral clips effec- 40 tive in action and hence said intermediate clip is a desirable coöperative element.

In Fig. 7 is shown a slightly modified form of the device and in this construction the sections 3' and 4' conform exactly in construction being connected in exactly the 45 same manner as with respect to the preferred form to obtain relative movement or slipping connection of these parts. Adjacent to the end of each section, however, the 50 material is bent laterally and inwardly to form a recurved guiding element 7' spaced slightly from the major portion of its section, this bending forming a guide loop for performing exactly the same function as the 55 loop of the preferred construction formed by the elements 7, 8. The end 9 of each section in this modified form is bent at right angles from the recurved portion 7' and the extremities suitably apertured so as to en- 60 gage with the ends of the windowshade or roller, more strictly speaking. With this type of fixture, the shade indicated in dotted lines 10' is supported by any conventional type of bracket 2'', the fixture hereinbefore 65 described being supported from the shade

pivots and, therefore, pendent beneath the shade so as to properly perform its function which is identical with that of the preferred construction in that the shade is guided and limited with respect to its rolling action. 70

Having thus described our invention, what we claim as new is:

1. A windowshade fixture of the class described comprising adjustable sections overlapping and having their ends engaging 75 each other, and a locking member freely slideable on the overlapping portion when said sections are in adjusted positions, said member extending between the overlapping portions of the sections whereby on movement of the locking member toward an engaging end to cause binding action thereby locking the sections from relative movement.

2. A windowshade fixture of the class described comprising adjustable sections overlapping each other, and a locking member comprising a clip having its ends reversely bent about the overlapping portions of the sections and passing therebetween at its intermediate portion, the end of each section 85 being slidably engaged with the other section, whereby upon movement of the clip toward an engaging end to cause binding action tending to prevent relative sliding movement of said sections. 90

3. A windowshade fixture of the class described comprising adjustable sections overlapping each other, the end of each section being slidably engaged with the other section, locking means for holding the sections 100 at adjusted positions movably mounted on the overlapping portions, said means comprising wedging clips, and means associated with the clips for rendering the wedging action of said clips effective. 105

4. A windowshade fixture of the class described comprising adjustable rod sections overlapping each other, and locking means on the overlapping portions consisting of a plurality of clip members slidably engaging the overlapping portions and passing therebetween, certain of said clip members constituting wedge elements and one of said clip members intermediate those last-mentioned coacting to prevent yielding and separation of the overlapping portions during wedging action of the other clip members. 110

5. As a new article of manufacture, a windowshade fixture comprising a rod adapted to extend across a window, the material of the rod adjacent to each end being bent downwardly at right angles to its body portion, then inwardly from the right angle portion and back upon the inwardly bent portion in superposed relation thereto to 120 form a guide element adapted to coöperate at one side of the windowshade, the material then being bent outwardly and inwardly, then back upon itself in superposed relation and in parallel relation to the afore- 125 130

said rebent portion to form a guide element adapted to coöperate with the windowshade at its opposite side, the guide elements thus formed lying in the same horizontal plane, 5 each extremity of the rod element being bent upwardly from the guide elements to form an offstanding supporting arm for said shade, substantially as described.

In testimony whereof we affix our signatures.
